ROTARY BIT

Charles A. Dean, Compton, Calif.

Substitute for abandoned application Serial No. 137,404, April 17, 1937. This application December 1, 1938, Serial No. 243,401

4 Claims. (Cl. 255—71)

This invention pertains to improvements in earth-drilling bits, and particularly to means for mounting a rotatable cutter in a rotary bit.

This application is a substitute for my earlier filed application S. N. 137,404, filed April 17, 1937, and which became abandoned on April 6, 1939.

An object of this invention is to provide a cutter assembly that is sturdy, and also one that is adapted to minimize wear and looseness of a cutter in its support. A further object is to provide a simple assembly and in large measure to utilize replaceable parts. The invention consists in the parts and combination and arrangement thereof illustrated in the accompanying description and drawing and particularly pointed out in the appended claims.

In the drawing, the figure shows a bit head partly in elevation and partly in vertical section through a roller cutter and mounting therefor, according to a preferred embodiment of this invention.

According to the present invention a rotatable cutter is provided with a projecting hub portion for support upon a trunnion bearing. More particularly the projecting hub is arranged within a wear washer supported in the bit head to absorb both upward and side thrusts in use. In a specific embodiment of this invention, as at present preferred, a roller cutter is formed with a projecting hub directed inwardly toward the center of the bit head, and is mounted on trunnions between supporting legs of the bit head with a flange of wear-resistant material around the hub portion of the cutter. As such wear-resistant material, "stellite" or other well-known substances are suitable.

Referring more particularly to the drawing, there is shown a rotary bit-head 1 with roller cutters 2, 3 mounted between opposite pairs of legs or support arms 4, 5 and 6, 7 formed at the bottom of the bit head. Between these outer cutters are inner cutters illustrated by 8 in the drawing. A portion of the bit head is cut away near cutter 3 to illustrate the mounting of the outer cutters.

Cutter 3 is shown with an elongate hub portion 9 supported upon a trunnion bolt 10, which is secured to the bit head. Hub portion 9 is adapted to space the cutter 3 away from the bit head leg adjacent to the hub sufficiently for a wear-resistant flange 11 to be secured in the space thus provided. In the specific form shown in the drawing hub 9 projects from cutter 3 toward the inner leg 6 of the bit head so that annular washer

11 of wear resistant material may be inserted between cutter 3 and leg 6 and preferably to bear against leg 6 and the fronting face of cutter 3. A further preferred feature of this invention resides in providing a portion of leg 6 concentric with hub 9 so as to receive ring 12 of wear resistant material as a sleeve axially of the cutter hub. As shown in the drawing this may be accomplished by recessing leg 6 of the bit head sufficiently to receive ring 12. As shown, ring 12 and washer 11 may be unitary with each other; this in the claims is designated as a flange. By such means extensive bearing and wear-resistant surface is provided for the cutter. Moreover a snug fit and extensive surface of wear resistant material 11, 12 along the hub 9 and adjacent face of the cutter assure continued alignment and minimum whipping or play of the cutter in use.

The advantages of this cutter mounting are enhanced by combining the above-described features of this invention with additional improvements. Thus trunnion bolt 10 is fitted through hub 9 and is supported by bifurcated legs 6 and 7 of the bit head. Bolt 10 is threaded to tighten cutter 3 against wear rings 11, 12. Further security is provided by flanged plug 13 inserted within a base in outer leg 7 of the bit head and threaded internally to receive bolt 10. Thus plug 13 may be drawn against the outer face of cutter 3. As shown, the outer face of cutter 3 is recessed to receive the flange of plug 13, while leg 7 of the bit head abuts against the outer side of this flange. As a specific feature of this combination, plug 13, the outer face of cutter 3, and the abutting portion of leg 7 are formed to receive low-friction bearings, such as rotatable bearings 14. In the arrangement thus shown, stress on the cutter is balanced and distributed between the wear washer 11, 12 and bearings 14, so that the bearings 14 are relieved of excessive pressure. Plug 13 in one form of this invention is split to permit insertion to form the ball race. When the cutter assembly is complete and trunnion bolt 10 drawn tight, the outer face of trunnion plug 13 is further secured, as by weld 15, to leg 7 of the bit head.

It will be evident that one advantage of this invention resides in provision to pre-assemble a cutter ready for quick replacement in a bit head in the field when necessary. A further advantage of considerable importance resides in the ability of wear washer 11, 12 and hub 9 to receive both upward and side thrust in use, particularly on an extensive inner surface of the cutter as shown, to distribute stress over an extensive

surface and to maintain alignment of the cutter despite extensive use.

While in accordance with the patent statutes a particular embodiment of this invention has been described, and the best mode of application now contemplated, for illustration of the principles thereof, it is evident that variations and other specific arrangements are contemplated and various adaptations of this invention may now be made by those skilled in the art, within the scope of the appended claims.

I claim:

1. In combination in an earth drill, a bit head comprising a pair of bifurcated support arms, a roller cutter with a bearing hub projecting from one face thereof, a wear-resistant element mounted as a sleeve about the hub to bear against the adjacent support arm, a trunnion bolt in one arm supporting the hub, and in the other arm a trunnion plug supporting the roller cutter and movably engaged by the trunnion bolt to be drawn against the roller cutter.

2. In combination in an earth drill, a bit head comprising a pair of support arms, a roller cutter with a bearing hub projecting from one face thereof, a wear resistant flange mounted around the hub against the adjacent face of the cutter, a rotatable low friction element mounted to bear against the opposite face of the cutter, a trunnion bolt extending through the hub to one of the adjacent support arms, a trunnion plug in the

opposite support arm formed to retain the rotatable low friction element and threadedly connected to the trunnion bolt to be drawn thereby against the face of the roller cutter.

3. In combination in an earth drill, a bit head comprising a pair of support arms, a roller cutter with a bearing hub projecting downwardly toward the center of the drill from the inner face of the cutter, a wear resistant washer mounted around the hub against the adjacent inner face of the cutter, a trunnion bolt extending through the hub to the inner support arm, a recessed portion in the outer face of the cutter and a rotatable low friction element mounted in the recess for support against the arm adjacent thereto, a trunnion plug in the recess and extending into the outer support arm and threadedly connected to the trunnion bolt to be drawn thereby against the face of the roller cutter.

4. An earth drill comprising in combination a bit head having secured thereto a supporting arm for a roller cutter, a roller cutter mounted thereon having a hub projecting toward the supporting arm and having a face adjacent the hub generally fronting the supporting arm, and an annular member of wear-resisting material fitted externally of the hub and against the adjacent face and the supporting arm, the supporting arm containing a recess to receive the hub and annular wear-resisting member.
